TELEPHONE HAND SET

Filed Dec. 30, 1922

Inventor:
LeRoy W. Kelsay,
by Jas Ch. Palmer, Att'y

UNITED STATES PATENT OFFICE.

LE ROY W. KELSAy, OF NEW YORK, N. Y., ASSIGNOR TO WESTERN ELECTRIC COMPANY, INCORPORATED, OF NEW YORK, N. Y., A CORPORATION OF NEW YORK.

TELEPHONE HAND SET.

Application filed December 30, 1922. Serial No. 610,032.

To all whom it may concern:

Be it known that I, LE ROY W. KELSAy, a citizen of the United States, residing at New York, in the county of Bronx, State 5 of New York, have invented certain new and useful Improvements in Telephone Hand Sets, of which the following is a full, clear, concise, and exact description.

This invention relates to telephone hand sets and particularly to hand sets intended for use by linemen.

The object of the invention is to provide an efficient, compact, rugged hand set which is cheap to manufacture and convenient to 15 handle.

In general, the invention comprises a hand set having a handle of insulating material with a groove in the face thereof for the receiver conductors, and a channel-shaped cover for said groove, held in place 20 by receptacles for the receiver and the transmitter.

In the drawings,

Fig. 1 is a front view of a hand set embodying the invention with the receiver and transmitter removed;

Fig. 2 is a side view, part in section;

Fig. 3 shows a cross-section of the handle at 3—3.

30 A handle 4, preferably of fibrous insulating material, impregnated with a phenol condensation product, supports at one end a receiver receptacle 9 and at the opposite end a transmitter receptacle 10. The bottoms of these receptacles are provided with openings, 15 and 16, respectively. The face of the handle 4 has a longitudinal groove 5 therein terminating under the receptacles 9 and 10. A channel-shaped member 8 is inserted into the groove 5 with which it forms a conduit for the receiver conductors 6. The ends of channel 8 are provided with outwardly projecting lugs 13 and 14 which engage the receptacles 9 and 10 in holes 15 and 16, respectively. The receptacles 9 and 10 are secured to the handle 4 by any suitable means, such as rivets 12, and they hold in place the channel member 8. While any suitable instruments may be used, the receiver 7 is preferably of the type disclosed in Patent No. 1,273,351 to H. A. Frederick, issued July 23, 1918, and the transmitter 17 is preferably of the type disclosed in an application, Serial No. 525,898, filed December 30, 1921 by H. F. Dodge, which

shows an arrangement whereby a small diaphragm, not substantially larger than the diameter of the usual carbon containing chamber, may be mounted between banks of thin paper washers sufficiently loose to permit it to vibrate at approximately the same amplitude as a considerably larger diaphragm. The cases of the receiver 7 and the transmitter 17 are provided with radially projecting studs 18 and 19 which register with slots 20 and 21 in the receptacles 9 and 10, respectively, for the purpose of facilitating the aligning of the instruments. The bottom of the case of transmitter 17 is provided with a terminal block for the purpose of making the usual circuit connections.

A handset of the character herein described is light, durable and efficient, and being comparatively small it is particularly adapted for use by linemen. By using a substantially rigid handle of fibrous material and providing receptacles at each end for the instruments a structure is obtained which is comparatively cheap to manufacture and maintain. Should the instruments become defective they may be readily replaced or should the handle become defective the instruments may be easily salvaged and used again without readjustment.

The invention claimed is:

1. A telephone hand set comprising a receiver, a transmitter, a receptacle for said receiver, a receptacle for said transmitter, a handle of insulating material having a groove in the face thereof communicating with said receptacles, and a cover for said groove held in place by said receptacles.

2. A telephone hand set comprising a receiver, a transmitter, a receptacle for said receiver, a receptacle for said transmitter, a handle of insulating material having a groove in the face thereof communicating with said receptacles, and a channel-shaped member inverted in said groove and forming therewith a conduit between said transmitter and said receiver and held in place by said receptacles.

3. A telephone hand set comprising a handle of insulating material having a longitudinal groove in the face thereof, a channel member inverted in said groove, and a receiver and a transmitter clamping the opposite ends of said channel member to said handle.

4. A telephone hand set comprising a receiver, a transmitter, a handle of fibrous insulating material having a groove in the face thereof, a receptacle for said receiver supported on one end of said handle, a receptacle for said transmitter supported on the opposite end of said handle, a channel-shaped cover invertedly inserted in the groove of said handle and terminating beneath said receptacles, and outwardly extending lugs on the ends of said cover engaging the receptacles.

5. A telephone hand set comprising a handle of insulating material having a longitudinal groove in the face thereof, a channel-shaped member invertedly inserted in said groove, a receiver receptacle at one end of said handle having a perforated base,

a transmitter receptacle at the opposite end of said handle having a perforated base, and 20 lugs on said channel-shaped member engaging said receptacles in said perforations to secure said cover in place.

6. A telephone hand set comprising a handle having a groove in the face thereof, a 25 channel-shaped member invertedly inserted in said groove, an outwardly projecting lug at each end of said channel member, and instruments mounted on the opposite end of said handle covering the ends of said channel and engaging the lugs to hold said channel in place.

In witness whereof, I hereunto subscribe my name this 28th day of December A. D., 1922.

LE ROY W. KELSBY.
